UNITED STATES PATENT OFFICE

168,213

COMBINED BATHROOM ASH TRAY AND
SUPPORTING BRACKET THEREFOR

Seymour Coller, Brooklyn, N. Y.

Application July 28, 1951, Serial No. 16,063

Term of patent 7 years

(Cl. D85—2)

To all whom it may concern:

Be it known that I, Seymour Coller, a citizen of the United States of America, residing at the Borough of Brooklyn, county of Kings, city and State of New York, have invented a new, original, and ornamental Design for a Combined Bathroom Ashtray and Supporting Bracket Therefor, of which the following is a specification, reference being had to the accompanying drawing, forming part hereof, wherein Fig. 1 is a perspective view of a combined bathroom ash tray and supporting bracket therefor, showing my new design; Fig. 2 is an exploded perspective view thereof; Fig. 3 is an exploded side elevational view thereof; and Fig. 4 is an exploded top plan view thereof.

I claim:

The ornamental design for a combined bathroom ash tray and supporting bracket therefor, substantially as shown.

SEYMOUR COLLER.
